UNITED STATES PATENT OFFICE.

CHARLES J. CALEY, OF NEW BRITAIN, CONNECTICUT, ASSIGNOR TO THE RUSSELL & ERWIN MANUFACTURING COMPANY, OF NEW BRITAIN, CONNECTICUT, A CORPORATION OF CONNECTICUT.

DESIGN FOR A KEY.

SPECIFICATION forming part of Design No. 36,740, dated January 19, 1904.

Application filed December 15, 1903. Serial No. 185,317. Term of patent 14 years.

To all whom it may concern:

Be it known that I, CHARLES J. CALEY, a citizen of the United States, residing at New Britain, in the county of Hartford, State of Connecticut, have invented a new, original, and ornamental Design for Keys.

In the drawings, Figure 1 is a view in side elevation of a key embodying my ornamental design. Fig. 2 is a similar view of the reverse side. Fig. 3 is a cross-section showing the outline of the key-shank.

What I claim as new, and desire to secure by Letters Patent, is—

The ornamental design for a key as herein shown.

CHAS. J. CALEY.
